[57] CLAIM

The ornamental design for a golf putter head, as shown and described.

DESCRIPTION

FIG. 1 is a rear perspective view of a golf putter head, showing our new design;

FIG. 2 is a front perspective view thereof;

FIG. 3 is a top plan view thereof, showing the upper surface of the golf putter head;

FIG. 4 is a left end elevation view thereof, rotated 90° showing the heel of the club head;

FIG. 5 is a front elevation view thereof, showing the striking surface of the golf putter head;

FIG. 6 is a right end elevation view thereof, rotated 90° showing the toe and the club head;

FIG. 7 is a bottom plan view thereof, showing the sole plate of club head; and,

FIG. 8 is a rear elevation view thereof, showing the rear side of the club head.
